(57) **CLAIM**

We claim the ornamental design of a furniture controller, as shown and described.

DESCRIPTION

FIG. 1 is a front, bottom, right perspective view of a furniture controller, showing our new design;

FIG. 2 is a rear, top, right perspective view of the furniture controller of FIG. 1;

FIG. 3 is a front elevated view of the furniture controller of FIG. 1;

FIG. 4 is a rear elevated view of the furniture controller of FIG. 1;

FIG. 5 is a top plan view of the furniture controller of FIG. 1;

FIG. 6 is a bottom plan view of the furniture controller of FIG. 1;

FIG. 7 is a right side elevated view of the furniture controller of FIG. 1; and,

FIG. 8 is a left side elevated view of the furniture controller of FIG. 1.

The broken lines in the drawings depict features that form no part of the claimed design.
